ROLL-OFF MOLDING MACHINE

Filed Feb. 5, 1936

UNITED STATES PATENT OFFICE

2,102,378

ROLL-OFF MOLDING MACHINE

William Henry Nicholls, Roslyn, N. Y.; William H. Nicholls, administrator of William H. Nicholls, deceased, assignor to Wm. H. Nicholls Co., Inc., Long Island, N. Y., a corporation of New York

Application February 5, 1936, Serial No. 62,523

7 Claims. (Cl. 22—9)

The invention relates to foundry equipment and has particular reference to what is known in the art and to the trade as a jolt, squeeze and roll-off molding machine.

5 It is well known that machines have been devised embodying means for applying to a flask any desired number of successive blows or jolts, by suitably controlled pneumatic means for the purpose of shaking and distributing the sand 10 properly about the patterns, subsequently to which a different piston is brought into operation for the purpose of squeezing the flask together with the sand and patterns therein so as to compress the sand firmly about the patterns 15 and thereby produce sharp and well defined molds in which high class castings may be made. Some machines of this general character are also provided with rollers adapted to be brought into 20 engagement with the flask, after the molding operation, so that the flask and the molds therein may be rolled off from the machine onto other appropriately located rollers ready for removal and the subsequent casting operation.

The present invention relates to machines of the 25 above mentioned type and has for its general object the provision of a roll-off structure which is movably mounted so as to be automatically swung out of the way of the flask at certain times and to be swung into operative relation to the 30 flask for supporting it at the conclusion of the squeezing operation, the position of the roll-off device being controlled by that of the top frame and squeeze head.

An important object of the invention is to provide 35 a roll-off device of this character which may be adjusted so as to permit the use of different sizes of pattern plates and flasks.

Still another object is to provide a device of 40 this character which may be applied as an attachment to already existing molding machines at present or initially unequipped with any roll-off device, the additions to existing machines being easily made and not involving any serious changes.

A more specific object of the invention is to 45 provide a molding machine with a roll-off device including laterally swingable bars each equipped with a series of rollers adapted to be engaged beneath the flask at the appropriate time for the purpose of enabling it to be slid off onto a suitable trackway without any jarring such as might dislodge or break down the molds within the flask.

An additional object is to provide a device or 50 structure of this character and for this purpose which will be simple and inexpensive to manufacture in addition to being easy to apply, positive

and automatic in action, efficient and durable in service, and a general improvement in the art.

To the attainment of the foregoing and other objects and advantages, the invention preferably consists in the details of construction and the 5 arrangement and combination of parts to be hereinafter more fully described and claimed, and illustrated in the accompanying drawing in which:

Figure 1 is a view partly in side elevation and 10 partly in vertical section illustrating the machine, a portion of the flask being broken away.

Figure 2 is a top plan view with part of the flask and base broken away.

Figure 3 is a fragmentary detail section taken 15 on the line 3—3 of Figure 1.

Referring more particularly to the drawing the machine is represented as including a base 10 formed centrally with a cylinder 11 and near its ends with guide sockets 12. Slidable within the 20 cylinder 11 is a squeeze piston 13 formed as a cylinder within which is in turn slidable a jolt piston 14 carrying a jolt and squeeze head 15 forming part of or engaging a top frame 16 upon which is adapted to be disposed a pattern carrying plate 17 upon which rests the flask 18 in which the molding of any desired patterns is to be carried out. The squeeze and jolt pistons 13 and 14, respectively, are adapted to be operated by pneumatic pressure, though said means is not 30 shown for the reason that it is old and well known and may be of any desired type for instance as illustrated in the patent to J. R. Dunbeck, No. 1,545,817 or in my prior Patent No. 1,472,807, the arrangement in said and also in other patents 35 being such that the jolt piston 14 is movable independently of the squeeze piston 13 whereas both the jolt and squeeze pistons move together during the squeeze operation.

For guiding purposes, the squeeze head 15 is 40 represented as having depending arms 19 carrying guide sleeves or sockets 20 slidably receiving pins or rods 21 extending downwardly from the top frame, and the top frame 16 is provided with arms 22 having downwardly offset ends 23 through 45 which are secured guide rods 24 which are slidably within the sockets 12, these sockets being preferably bushed at 25 and 26 so that wear can be taken up, it being important that the top frame 16 must have a smooth movement so as to avoid 50 disturbing the sand after the squeeze operation is completed and the squeeze head retreats from the top of the machine.

Though it is not illustrated herein, machines of this general type include an upstanding post 55

rising from the base and carrying a swingable arm equipped with a pressure head which is vertically adjustable as by means of a screw connection, for instance as illustrated in the above mentioned 5 Dunbeck Patent No. 1,545,817. The purpose of such a pressure head is of course to provide an abutment against which the top of the sand engages during the squeeze position of the machine. From known art it is thought that this 10 will be quite apparent.

In carrying out the present invention, the essential feature of which is the provision of novel roll-off means which will not interfere with downward movement of the parts at certain times but 15 which will support the flask after the molding operation, I provide at each corner of the base an elongated supporting bracket 27 bolted or cast into place and having an outwardly offset intermediate portion defining a slot 28. Mounted on 20 each of these brackets is a clevis 29 having a reduced stem portion 30 extending through the slot 28 and carrying a securing nut 31. These clevises are adjustable along the slots 28 in accordance with the size of the pattern plate and 25 flask desired to be used. Pivoted at 32 within each clevis is an upstanding arm 33 normally maintained in vertical position by virtue of the provision of a laterally extending counter-weight 34, or its equivalent, engaging a stop 35 on the 30 associated clevis. At their upper ends the arms 33 at each end of the machine carry horizontally disposed bars 36 on each of which is journaled a series of flanged rollers 37. These bars are outwardly offset at their central portions as shown 35 at 38 to accommodate or avoid interference with the ears 39 and 40 on the pattern plate and flask respectively, which ears are connected by dowel pins 41 for maintaining the flask in proper position upon the pattern plate.

40 When the arms 33 carrying the rollers 37 are in their vertical positions they are not in the path of vertical travel of the pattern plate, as clearly indicated at the right of Figure 2 but they are, however, in obstructing relation to 45 downward movement of the flask as shown at the left hand of Figure 2 inasmuch as the flask projects somewhat beyond the ends of the pattern plate. To effect movement of the arms outwardly so as to be out of the path of travel 50 of the flask, I provide at each corner portion of the top frame 16 an elongated guide or camming member 42 secured in place by studs 43 passing through elongated slots 44, the idea being to provide for adjustment of the guides or camming members 42 in accordance with the adjusted positions of the clevis members 29. These guide or 55 camming members 42 engage against the inner edges of the arms 33 which have their upper portions partly cut away at 45 to provide inclined cam or wedging surfaces 46, it being clear that when the top frame 16 is in lowered position the guide or camming members 42 riding over the inclined cam or wedge surfaces 46 and travelling down the inner edges of the arms 33 to their lowermost positions indicated by the dot and dash lines at 47 in Figure 1 will swing the arms 33 outwardly upon their pivots 32, thereby moving the bars 36 outwardly so that the rollers 37 carried thereby will be in the positions shown by dot and dash lines in Figure 1, the rollers being then 70 out of the path of travel of the flask.

In the use of the machine, it should be understood that at the very outset the clevis members 29 must be adjusted along the slots 28 and that 75 the guide or camming members 42 must be simi-

larly adjusted by means of the studs 43 passing through the slots 44, all in accordance with the size of the pattern plate and flask which are of course arranged in superposed relation upon the top frame 16 and connected by the dowels 41. 5 The desired patterns are supported upon the pattern plate 17 and sand is poured into the flask 18 so as to surround the patterns. The drawing shows the jolt and squeeze head 15, the top frame 16, pattern plate 17 and flask 18 in their positions 10 of maximum elevation. However, the initial position of the parts is their lowered one with the squeeze piston 13 at the bottom of the cylinder 11 and it is at this time that the flask and pattern are placed in position and the sand poured 15 into the flask. It should of course be understood that at this time, that is to say when the parts 13, 14, 15, 16, 17 and 18 are in their lowered position the arms 33 carrying the bars 36 equipped with the rollers 37 are in their divergent relationship. Whatever control means is provided, not shown as forming no part of the present invention and as being old and well known in the art, is then operated to admit compressed air beneath the jolt piston 14 which is caused, 20 likewise by means old in the art, to reciprocate vertically rather rapidly for the purpose of jolting the pattern plate and flask and thereby settling the sand about the patterns. Subsequently to this, whatever control means is provided is 25 actuated to admit fluid pressure into the squeeze cylinder 11 so that the squeeze piston 13, together with the then inactive jolt piston 14 will be forced upwardly, the squeeze head 15 then applying upward pressure against the top frame 16 and 30 through the pattern plate 17 to the sand within the flask 18 so that the sand will be thoroughly compressed about the patterns and between the pattern plate 17 and the pressure plate or head, above referred to but which is not illustrated as 35 being old and well known. This completes the molding operation. As the top frame 16 moves upwardly to perform the squeeze operation the guide or camming members 42 ride off from those 40 portions of the inner edges of the arms 33 below 45 the inclined shoulders 46, ride upwardly over the shoulders 46 and against the inner edges of the cutaway portions 45 at the upper ends of the arms 33. The counter-weights 34 at the lower 50 ends of the arms 33 then operate to restore the arms 33 to their vertical positions. The pneumatic control means is then operated to release the air pressure beneath the squeeze piston 13 so that this squeeze piston together with the squeeze head 15, top frame 16 and pattern plate 17 may 55 move downwardly to the normal or lowered position. However, as the arms 33 are then vertically disposed the rollers 37 will be in the path of travel of the flask 18 which will descend until its ends rest upon the rollers so that it may be pushed 60 off onto whatever trackways or other guide rollers are provided at either side of the machine. The remaining parts are permitted to continue their descent whereupon the guide or camming members 42 will again move the arms 33 and rollers 37 outwardly so that the cycle of operations 65 may be repeated.

From the foregoing description and a study of the drawing it will be apparent that I have thus provided a very simply constructed combined 70 jolt, squeeze and roll-off molding machine in which the roll-off mechanism is inactive or ineffective when the machine parts are in normal or lowered position but are automatically moved into operative position for supporting the flask to en- 75

able it to be rolled off when the molding operation has been completed. It is thought from the above that the construction, operation and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In a molding machine including a base carrying a squeeze cylinder, a squeeze piston slidable within said cylinder and formed with a jolt cylinder, a jolt piston slidable within said jolt cylinder and carrying a jolt and squeeze head, a top frame supported by said squeeze head, laterally positioned guiding means for said frame, a pattern plate connected to said frame and normally adapted to engage and support a flask, roll-off mechanism for said flask comprising a pair of roll bars adapted to underlie adjacent portions of said flask, arms for pivotally and adjustably supporting said bars, and adjustable means carried by said frame for maintaining said roll bars out of the path of movement of the said flask during a portion of the downward movement of said frame.

2. In a molding machine including a base carrying a squeeze cylinder, a squeeze piston slid-
able within said cylinder and formed with a jolt cylinder, a jolt piston slidable within said jolt cylinder and carrying a jolt and squeeze head, a top frame supported by said squeeze head, laterally positioned guiding means for said frame, a pattern plate connected to said frame and normally adapted to engage and support a flask, roll-off mechanism for said flask comprising a pair of bars carrying rollers positioned on opposite sides of said squeeze head, each of said bars having an offset portion to clear said adjacent frame guiding means, and arms for pivotally and adjustably supporting said bars, and adjustable means carried by said frame for maintaining said bars out of the path of movement of said flask during a portion of the downward movement of said frame.

3. In a molding machine including a base carrying a squeeze cylinder, a squeeze piston slid-
able within said cylinder and formed with a jolt cylinder, a jolt piston slidable within said jolt cylinder and carrying a jolt and squeeze head, a top frame above the squeeze head supporting a pattern plate carrying a flask, upstanding arms pivoted on the machine, a roll bar carried by each pair of said arms, means tending to normally maintain said arms in position with said roll bars in the path of downward movement of the flask, and means carried by said squeeze head and adapted to engage said arms to force the same out of the path of downward movement of said head after a predetermined movement of said head, and means carried by said arms for continually urging said arms into load supporting position.

4. In a molding machine including a base carrying a squeeze cylinder, a squeeze piston slid-
able within said cylinder and formed with a jolt cylinder, a jolt piston slidable within said jolt cylinder and carrying a jolt and squeeze head, a top frame supported by said squeeze head, laterally positioned guiding means for said frame, a pattern plate supported on said frame and adapted to normally engage and support a flask, roll-off mechanism for said flask comprising a pair of roll bars and a pair of arms for pivotally and adjustably supporting each of said bars, means continually urging said roll bars into flask engaging position, and means carried by said frame and movable therewith for forcing said bars out of flask supporting position upon downward movement of said squeeze head to normal position.

5. In a molding machine including a base carrying a squeeze cylinder, a squeeze piston slid-
able within said cylinder and formed with a jolt cylinder, a jolt piston slidable within said jolt cylinder and carrying a jolt and squeeze head, a top frame above the squeeze head supporting a pattern plate carrying a flask, upstanding arms pivoted on the machine, a plurality of roll bars carried by said arms, means carried by the arms for normally maintaining said roll bars in the path of downward movement of the flask, and means operating upon downward movement of said top frame to swing said arms outwardly to move said rollers out of flask engaging position, the pivots of said arms and the means carried by said top frame and cooperating with the arms for moving them being both adjustable laterally to accord with flasks of different dimensions.

6. In a molding machine, a base, a top frame carrying a pattern plate for supporting a flask, jolt and squeeze means reacting against said top frame, brackets mounted on the base, pivot elements laterally slidably adjustable along said brackets toward and from each other, upstanding arms pivoted on said pivot elements, guide members mounted on the top frame and reacting against said arms for swinging the same laterally out of the path of travel of the flask, and means for adjusting said guide members toward or from each other to accord with the adjustability of said pivot elements.

7. In a molding machine, a base, a top frame carrying a pattern plate supporting a flask, jolt and squeeze means reacting against said top frame, and roll-off means comprising longitudinally slotted brackets mounted in a horizontal position upon the base, bolts extending vertically through said slotted brackets and adjustable therealong, upstanding arms pivoted on said bolts and formed with inclined surfaces, the arms on each side of the machine carrying bars, rollers mounted on said bars, guide members mounted in horizontal positions upon the top frame for co-action with said inclined surfaces for moving said arms out of the path of travel of said flask, and means for adjusting the positions of said guide members in accordance with the adjustment of said pivot bolts to enable the parts to accommodate flasks of different sizes.
